UNITED STATES PATENT OFFICE.

EARL F. HESS, OF JAMISON CITY, PENNSYLVANIA.

MECHANICAL WALKING TOY.

1,261,528.

Specification of Letters Patent.

Patented Apr. 2, 1918.

Application filed December 4, 1916. Serial No. 135,017.

To all whom it may concern:

Be it known that I, EARL F. HESS, a citizen of the United States, residing at Jamison City, in the county of Columbia and 5 State of Pennsylvania, have invented certain new and useful Improvements in Mechanical Walking Toys, of which the following is a specification.

The present invention relates to automatic 10 toys and more particularly to that type of automatic toy such as walking dolls, animals, or the like.

The main object of the invention is the provision of automatic toys of the above 15 character which possess a simple construction and are inexpensive to manufacture and whose actuating parts are so arranged as to produce an effective operation of the toy.

20 The invention resides in novel features of construction and combination and arrangement of parts hereinafter more fully described and finally pointed out in the appended claims.

25 In the drawings which illustrate the invention:—

Figure 1 is a side view of the toy the parts broken away to illustrate the arrangement of the actuating mechanism.

30 Fig. 2 is a front view of the invention a portion of the casing broken away to illustrate the actuating mechanism, and

Fig. 3 is a detail view of a roller.

Like characters denote similar and like 35 parts throughout the specification and drawings:—

The automatic toy according to this invention is illustrated in the drawings as partaking the configuration of a bear, however, it is to be understood that the body of the toy may be of any other desired configuration. The toy may be made of metal or any desirable material and 1 indicates a body of the toy having a head 2 pivoted to the body at back or rear portions thereof as indicated at 3. Within the hollow body 1 is vertically disposed a frame 4 preferably secured and resting upon the bottom or lower portion 5 of the body. This frame 4 is designed to support a motor 6 and provide bearings for other operating parts hereinafter referred to. Arms or front legs 7, as the case may be, are pivotally secured to the body adjacent the head by the rods 8. 55 One end of each rod 8 is rotatably mounted on the upper portion of the frame 4 and is

extended outwardly through the body 1 and through the arm 7 where said extended end is secured to the latter. An intermediate portion of the rods 8 is bent or otherwise 60 suitably formed to provide cranks 9. Legs 10 are secured and are so formed so as to be applied and neatly conform to the lower or rear portion of the body 1. These legs 10 are held in position with respect to the body 65 by the rods 11 which have one end pivotally connected to the body as at 12 and the other end pivotally connected to the leg at its foot portion as indicated at 13, the foot portion of each leg 10 having journaled, at its heel 70 and toe portion, a roller 14. One of these rollers is provided with a serration of ratchet teeth 15 which are designed to engage with a pawl 16. This pawl and ratchet arrangement is designed to prevent one leg 10 from 75 moving rearwardly while the other leg is being advanced by the actuating mechanism later referred to, it being understood that the rollers 14 engage the floor or ground.

The motor 6 is disposed on a shaft 16 rotatably journaled in the frame and may be of any desired type, however, for the purposes of illustration, is shown as consisting of a coil spring having its inner end secured to the shaft 16 and its outer end secured to an arm 17 rigidly carried by the frame 4.

A gear wheel 18 is also rigidly carried on the shaft 16 and meshes with a suitable speed increasing gearing consisting of the pinion 19 and a gear 20 mounted on the shaft 21, supported in the frame 4, the gear 20 in turn meshing with the pinion 22 rigid on the crank shaft 23, which is also rotatably journaled in the frame 4. The opposite ends 95 of the crank shaft 23 rigidly carry the cranks 24. Each crank 24 is connected with the corresponding and overlying crank 9 of the rods 8 by a link or connecting rod 25. A rod 26 is also connected with one of the 100 cranks 9 and is pivotally connected to the head 2 at a forward point as at 27. It will thus be seen that as the motor operates the gear above referred to the crank 24 will operate the cranks 9 and thereby effect an up 105 and down or oscillating movement of the arms 8 and that the head 2 will also be rocked upon the pivot 3 through the medium of the rod 26. The cranks 24 on the opposite ends of the shaft 23 are so arranged that when 110 one of the arms 8 is moved downwardly the other arm will be moved upwardly and

thereby effect an alternating up and down motion of the arms. Each of the legs 10 of the toy are to be so actuated as to be moved forward in advance of the other alternately 5 to effect a walking movement. This movement of the legs is produced by the rods 28, one for each leg, having one end pivotally mounted in the frame 4 and the other end extended through the casing and directed 10 downwardly to a point adjacent the foot portion of the leg, where it is secured as indicated at 29. Each rod 28 is provided at an intermediate portion with a crank 30 which is connected to the overlying crank 24 by 15 the link 31.

It will thus be further seen that as the shaft 23 rotates the cranks 24 will actuate the cranks 30 in such a manner as will tend to effect an oscillation of each leg 10 in 20 opposite directions, although, in view of the pawl and ratchet arrangement 15 and 16, one of the legs 10 will be held against backward movement as the other leg is being brought forward by the operation of 25 its respective crank 30; and that the operation of the other crank 30, which would effect a backward movement of the leg being held against such movement, does instead, in view of said ratchet means, produce a forward movement of the body 1 relative to 30 said last mentioned leg as the opposite leg 10 is brought forward. It is in view of the steady alternative advancement of each leg 10 and the forward movement of the body 1, 35 caused in the manner just described, that an even balancing of the toy is produced and which effects an efficient walking operation thereof.

For the purpose of rewinding the motor 10 40 after the same has become unwound, the shaft 16 is provided with a key engaging end 32 and the toy 1 is formed with a suitable opening 33 which permits the insertion of a suitable winding key.

45 The foregoing clearly sets forth my invention, however, it is to be understood that certain changes in the construction and combination of parts may be resorted to as fall within the legitimate scope of the appended 50 claims.

What is claimed is:—

1. A mechanical toy of the class described comprising, a body portion, legs pivoted to the body portion, and means for effecting an 55 alternative advancement of said legs with respect to said body portion and for effecting a forward movement of the body portion synchronically with the advancement of each leg, when the toy is in an operative position 60 on the ground, said means including cranked connecting rods that have one end connected to the foot portions, the arms and head being operated from crank shafts through coupling rods.

2. A mechanical toy of the class described 65 comprising, a body portion, a head pivoted to said body portion, arms or legs pivoted to the body portion adjacent said head, supporting legs pivoted to the other end of the body portion, actuating means for effecting an 70 alternative advancement of said legs with respect to said body portion and for effecting a forward movement of the body portion synchronically with the advancement of each supporting leg, when the toy is in 75 an operative position on the ground, a radius rod connected between the body and the lower end of each leg for determining the relative movement therebetween, and means for connecting the head, arms and 80 legs with the actuating means, said means including connecting and coupling rods directly connected with cranks, certain of the connecting rods having one of their ends connected adjacent the lower end of each 85 leg, said head and arms being connected for movement simultaneous with the leg movement.

3. A mechanical toy of the class described comprising a body portion, supporting legs 90 pivoted to said body portion, means for preventing the backward movement of said legs, when the toy is placed in operative position on the ground, and means for alternatively advancing said legs with respect 95 to the body and for effecting the forward movement of the body portion synchronically with the forward movement of said legs, when the toy is on the ground, said means including a connecting rod having one end 100 connected with the lower end of a leg.

4. A mechanical toy of the class described comprising, a body portion, supporting legs pivoted to the body, means for oscillating said legs in opposite directions to produce 105 a forward progressive movement, means for preventing the backward movement of said legs with respect to the body when the toy is placed upon the ground in an operative position, said first means including connecting rods having their lower ends connected to the lower ends of the legs and their upper ends terminating in cranked portions for producing the oscillating movement of the legs.

5. A mechanical toy of the class described comprising, a body portion, supporting legs pivoted to the body portion, ground engaging rollers journaled in the free ends of said legs, automatic means for oscillating said 120 legs in opposite directions, means for preventing said rollers from rotating rearwardly while permitting the same to rotate forwardly to prevent backward movement as the body is caused to move forwardly by the 125 operation of said actuating means, said means including connecting rods directly connected to the free ends of the legs for

positively oscillating them, and a radius rod in each leg to determine the path of travel of the leg.

6. A mechanical toy of the class described comprising, a body portion, a pair of supporting legs pivoted to said body portion, automatic actuating means disposed in said body portion and adapted to cause said legs to oscillate in an opposite direction, said 10 means comprising connecting rods having their lower ends connected to the lower end of the legs, ground engaging rollers pivoted at the free ends of said legs, and locking means for preventing said rollers from rotating rearwardly, substantially as for the 15 purposes set forth.

7. A mechanical toy of the class described comprising, a body portion, a pair of supporting legs pivoted to said body portion, 20 a pair of arms pivoted to said body portion, a frame vertically disposed in said body portion, a motor supported in said frame, a crank shaft journaled in said frame and geared to said motor, links and cranked rods 25 for connecting said crank shaft with the lower ends of said supporting legs whereby said legs are oscillated in opposite directions, and links connecting said crank shaft with said arms whereby said arms are oscillated 30 simultaneously with said legs.

8. A mechanical walking toy of the class described comprising a body portion, supporting legs pivoted to said body portion, a head pivoted to said body portion, a frame vertically disposed in said body portion, a motor supported on the frame, a crank shaft journaled in said body and geared to said 35 motor, links and cranked rods for connecting said crank shaft with the lower ends of said supporting legs whereby said legs are oscillated in opposite directions, and links 40

connecting said crank shaft with said head whereby said head is oscillated simultaneously with said legs.

9. A mechanical toy, which comprises a 45 body, a head hingedly connected thereto, arms adapted to oscillate, legs capable of being oscillated, actuating means disposed within the body for producing a forward movement of the toy by causing the legs to 50 oscillate, and upon such movement the head is moved and the arms oscillated, means to prevent a backward movement of the toy, said actuating means including a plurality of crank shafts, a cranked connecting rod 55 for each leg and having its lower end attached adjacent the lower end of the leg, the cranked portions being connected by means of coupling rods with the crank shafts, and a radius rod to limit the oscillating movement of the legs relative to the 60 body.

10. A mechanical walking toy, which comprises a body having pivotally mounted arms and legs, and a hingedly connected head, actuating means within the body, said means including a shaft having cranks at its end, and connecting and coupling rods, said connecting rods forming the pivotal mounting 65 for the legs and arms, and comprising 70 cranks, the leg rods being connected at the lower ends of the legs, said coupling rods connecting the connecting rod cranks with the crank shaft, means for preventing backward movement of the toy, and means for 75 limiting the oscillation of the legs.

In testimony whereof I affix my signature in presence of two witnesses.
